US00D751897S

(12) **United States Design Patent**
Barad et al.

(10) **Patent No.:** **US D751,897 S**
(45) **Date of Patent:** **** Mar. 22, 2016**

(54) **PACKAGING**

(71) Applicant: **Microsoft Corporation**, Redmond, WA (US)

(72) Inventors: **Vivian Barad**, San Francisco, CA (US); **Ricardo Figueiroa Monteiro**, San Francisco, CA (US); **Scott Tong**, San Francisco, CA (US); **Jeffrey Allen Loth**, Sammamish, WA (US); **Robyn Lynne Yoder**, North Bend, WA (US)

(73) Assignee: **Microsoft Corporation**, Redmond, WA (US)

(**) Term: **14 Years**

(21) Appl. No.: **29/525,852**

(22) Filed: **May 4, 2015**

Related U.S. Application Data

(62) Division of application No. 29/449,971, filed on Mar. 15, 2013, now Pat. No. Des. 730,175.

(51) **LOC (10) Cl.** **09-03**

(52) **U.S. Cl.**

USPC **D9/432**

Assistant Examiner — Keith Frank

(74) *Attorney, Agent, or Firm* — Banner & Witcoff, Ltd.

(57) **CLAIM**

The ornamental design for packaging, as shown and described.

DESCRIPTION

FIG. 1 is a front perspective view of packaging showing our new design;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The broken line showing of the front surface portions and the unshaded region therein in FIGS. 1-7 is to depict unclaimed features only and forms no part of the claimed design.

1 Claim, 4 Drawing Sheets
